ART WINDOW AND METHOD OF MAKING
THE SAME

Ludwig L. Blake, South Bend, Ind.

Application January 21, 1933, Serial No. 652,817

3 Claims. (Cl. 20—56)

The invention relates to window constructions, paneled frames and the like, and to methods of making the same. More particularly the invention relates to decorative windows, whose frame members are provided with configured corners and which are otherwise configured.

The use of windows and paneled frames having configured corners and frames has heretofore been largely impractical because of the high cost of a sash provided with configurations, particularly configured corners for the light openings, and also because of the difficulty and expense of cutting glass panes or panels to fit into such configured frames. Likewise, where multiple pane windows were involved, the provision of a configured corner between the sash and the muntin and transom bars has been too difficult and expensive to permit use of such windows and paneled frames in any but monumental or like buildings.

It is therefore the primary object of my invention to provide an inexpensive construction of this character.

A further object is to provide a configured member carried by the frame and overlying a portion of the pane or panel to impart a configured appearance to the frame.

A further object is to provide a configured decorative member with means adapted to be imbedded in window putty to hold the same in operative position on the window.

A further object is to provide a method by which a conventional window having rectangular light openings therein may be converted into a window having configured light openings, and particularly configured corners.

With the above and other objects in view, the invention resides in the combination and arrangement of parts and in the steps of the method, as hereinafter set forth, shown in the drawing, described and claimed, it being understood that changes may be made in the precise embodiment of the invention without departing from the spirit of the invention.

45 In the drawing:

Figure 1 is a view of a window in front elevation.

Figure 2 is a perspective view of a four cornered member to be applied to the window.

50 Figure 3 is a transverse sectional view taken on line 3—3 of Figure 1.

Figure 4 is a perspective view of a two cornered decorative member.

55 Figure 5 is a perspective view of a single cornered decorative member.

Figure 6 is a fragmentary plan view of a window with parts shown in section on line 6—6 of Figure 3.

Figure 7 is a view in front elevation of a modified construction of my device.

Referring to the drawing, which illustrates the preferred embodiment of the invention, the numeral 10 designates a multiple pane window sash provided with muntin bars 11 and transom bars 12, said bars being of similar construction. A 10 plurality of window panes 13 are mounted in the sash in the usual manner by the use of putty 14.

The window panes having been mounted in the sash, corner pieces 15 are applied thereto at the corners thereof. These corner pieces may be 15 single corner pieces 16, as illustrated in Figure 5; two cornered members 17, as illustrated in Figure 4, which fit over a transom or muntin bar at the edge of the sash; or four cornered members 18, as illustrated in Figure 2, which fit over 20 the transom and muntin bars at their intersection. Each of the members 16, 17 and 18 is formed of thin sheet metal and comprises an upper or face plate 19 which lies parallel to and in contacting 25 relation with the surface of the side of the door frame, muntin or transom bar. This plate 19 may be suitably die pressed or embossed to provide an ornamental portion 20 therein. The plates 19 are shaped to provide the curvature or configuration desired for each window corner, and are provided at their curved edges with angularly 30 downwardly directed flanges 21. The angle at which flanges 21 extend relative to the plate 19 coincides with the angle on which the exposed 35 surface of putty 14 is finished, and the flanges 21 therefore lie flush with the putty when installed. At each end of the flanges 21 is provided an inwardly directed tab 22. These tabs are pressed 40 into the putty 14 in the installation of the corner pieces and while the putty is still soft, and, being so imbedded in the putty, form the means of attachment of the corner pieces, said tabs being effectively maintained in desired position by the putty after the putty has set and hardened.

In the installation of the corner pieces, the putty 14 need not extend fully to the corner of the frame, or, if it does fully encircle the window, the corners thereof need not be trimmed because they are covered by the corner members. Thus 50 the difficulty of handling putty in corners, to trim the same neatly, is eliminated. After the corner pieces have been installed, with their tabs impressed in the putty, the putty may be trimmed to extend flush with flanges 21 at their ends, and 55

an even bevel having no interruptions is provided about the entire window. The window frame and corner pieces may then be painted, and the corner pieces become invisible, except for the ornamental 5 embossed portions 20, which add to the appearance of the whole. If desired, the paint may be wiped from embossed portions 20 to leave the metal exposed, or a trim paint may be applied thereto to set off the same. In either case a novel 10 decorative appearance, as illustrated in the lower portion of Figure 1, is obtained.

It will be seen that, in addition to the decorative features obtained by the use of these corner members, the arcuate corners illustrated provide 15 a distinct utilitarian advantage by making the windows easy to wash, inasmuch as the bothersome angular corners, to which access is difficult, have been eliminated.

As illustrated in Figure 7, the invention is not 20 limited to the use of corner pieces alone, or to the use of round cornered members. In this figure the frame 30 is provided with a muntin bar 31 and a transom bar 32, and mounts panes or panels 33 therein. At the corners of the frame are 25 applied corner pieces 34; at the joints between the frame and the end of bars 31 or 32 are applied double corner pieces 35; and at the intersections of the muntin and transom bars are mounted the quadruple corner pieces 36. These 30 corner pieces are shaped to provide configured, rather than round, corners, and may be of the same construction as illustrated in the preferred embodiment of the invention, or a construction secured to place by brads 37 or other 35 suitable means to form the sole means for holding the window pane in the frame. Additional decorative members 38 may be employed, which members are disposed in spaced relation to the corners of the frame to overlie a portion of the pane 40 in the same manner as the corner pieces. These members provide additional means for imparting a configured appearance to the frame.

The invention having been set forth, what is claimed as new and useful is:

1. The combination with a paneled structure having raised muntin bars defining panels, and a corner piece comprising a configured plate and spaced complementary flanges extending angularly from the configured edges of said plate, said corner piece being positioned with said plate spanning said muntin bar and said flanges extending inwardly toward adjacent panels to fit 10 in adjacent corners thereof whereby said panels are provided with complementary configured outlines at their corners.

2. The combination with a window sash having muntin bars providing a plurality of angular cornered light openings therein, a pane mounted in each of said openings, and putty securing said panes in said openings, of a corner piece comprising a plate provided with at least two configured edges, a flange extending angularly 20 of said plate at each configured edge, said corner piece being positioned with said plate spanning at least one muntin bar and said flanges each fitting into a corner of adjacent light openings whereby said openings are provided with configured corners, each flange having a tab extending angularly thereto and imbedded in said putty to hold said corner piece in operative relation to said sash and panes.

3. The combination with a window sash having a muntin bar providing a plurality of light openings therein, a pane mounted in each opening, and putty securing said panes in said openings, of a plate having a pair of opposed configured edges, a flange extending angularly of said plate from each configured edge, said plate spanning said muntin bar with said flanges extending inwardly toward said panes and each cooperating with said putty to provide a configured pane outline, and a tab carried by each flange and imbedded in said 40 putty to hold said flanges and plate in operative relation to said sash and panes.

LUDWIG L. BLAKE.
